UNITED STATES PATENT OFFICE.

WILLIAM E. PRICE, OF WHITE PLAINS, NEW YORK.

DESIGN FOR A LIGHT-REFLECTOR FIXTURE.

Application filed October 30, 1925. Serial No. 15,295. Term of patent 14 years.

To all whom it may concern:

Be it known that WILLIAM E. PRICE, a citizen of the United States, and resident of White Plains, in the county of Westchester and State of New York, has invented a new, original, and ornamental Design for Light-Reflector Fixture, of which the following is a specification, reference being had to the accompanying drawing, forming part thereof, in which—

Fig. 1 is a front elevational view of a light reflector fixture embodying my new design; and

Fig. 2 is a bottom plan view thereof.
I claim:

The ornamental design for a light reflector fixture, as shown.

Dated New York city, October 17th, 1925.

WILLIAM E. PRICE.
